UNITED STATES PATENT OFFICE.

CHARLES E. BEDAUX, OF GRAND RAPIDS, MICHIGAN.

CALL-RECORDING APPARATUS FOR TELEPHONES.

1,291,731.

Specification of Letters Patent.

Patented Jan. 21, 1919.

Application filed November 22, 1916. Serial No. 132,742.

To all whom it may concern:

Be it known that I, CHARLES E. BEDAUX, a citizen of the Republic of France, residing at Grand Rapids, in the county of Kent 5 and State of Michigan, have invented new and useful Improvements in Call-Recording Apparatus for Telephones, of which the following is a specification.

The present invention relates to call recording apparatus for telephones, and its object is, generally, to provide improved apparatus whereby the person calling by telephone may record at the telephone called the number of the calling telephone in case 10 his call meets no response; and more particularly, to provide such an apparatus which, with its movable markable element for receiving such numbers, shall not be in operative movement except when the telephone is called.

This and any other objects appearing hereinafter are attained by, and the invention finds preferable embodiment in, the 15 illustrative structure hereinafter described and illustrated by the accompanying drawings, in which:—

Figure 1 is a front view of a telephone and my call-recording apparatus with the electric calling and call-recording circuit 20 therefor, including a suitable source of electric energy, diagrammatically shown;

Fig. 2 is a view of the call-recording apparatus, the front of its casing being removed and certain parts sectioned on a vertical plane to show the far half only of the electromagnet, for the sake of clearness;

Fig. 3 is a sectional view of the same taken on a horizontal plane corresponding to line A—B of Fig. 2;

Fig. 4 is a view of the same looking from the right-hand side of Fig. 2;

Fig. 5 is a detail view of mechanism for stopping and releasing the clockwork which moves the markable element; and,

Figs. 6, 7 and 8 are views of the same in different positions.

In the embodiment of the invention chosen for detailed description in the body of this specification and for illustration by the 50 drawings, a markable element adapted to be marked by a marker, as hereinafter explained, is movable relatively to such marker. As illustrated by the drawings the markable element, a paper strip 1, is moved at uniform speed by means of suitable clockwork (designated generally 2) by a feed

roll 3 on one of the clockwork's shafts 4, and passes between said roll and a suitable presser roll 5. The strip is thus drawn from a reel 6 and over the idler roll 7 whereon it is marked in passing by a marker, as the pencil 8. This marker is vibrated sidewise to make the marks on the strip shown in Fig. 3 by being operatively connected to a member movable by the calling apparatus, such member being the pivotally mounted armature 9 of the electro-magnet 10 in a branch 11 of the electric circuit 12 which includes the calling apparatus, indicated by the call bells 13, of the called telephone 14.

When the person calling presses the call button, indicated at 15, of his calling telephone, the bells ring and the pencil vibrates. Thus, a system of markings by dots and dashes being predetermined, the person calling by closing the circuit as by pressing the call button of his own telephone, may record on the markable element of the call-recording device of the called telephone 14 the proper combination of dots and dashes, represented by the zigzag marks 16, which indicates the member of the calling telephone.

When the call button is pressed, the vibration of the movable member (the armature 9) strikes a pin 17 of the movable releasing member 18 carried by a rotatable element 19 of the clockwork, and moves it out of the holding engagement of the detent pin 20 (see Fig. 5), whereupon the spring 21 presses the releasing member upwardly, it sliding in its slots 22, 23, an angularly disposed extension 24 of one of which slots has previously held the releasable member against said spring by engaging the detent pin 20. The upper end of the releasing member now strikes and raises the pin 25 of the movable and pivotally mounted stop 26 out of the notch or contact portion 27 of the rotatable element (see Fig. 6) and against the pressure of the spring 28, so that the clockwork is no longer stopped, but is permitted to run and move the record strip. During a rotation of the rotatable element 19, the pin 25 rides on its periphery (see Fig. 7) and the person calling may during this time record his call on the moving strip, the time required for such rotation being of course so regulated as to afford sufficient time for such recording. If the person calling presses the call button of his own telephone for a long time (for instance) to call the called telephone, the clock work is released and a long dash is made

on the markable element. If he receives no response, he immediately and while the clockwork continues to run, presses his call button a number of short and long times to correspond with the combination of dots and dashes which identifies his own telephone by its number. As the rotatable element continues its turning movement, the pin 29 of the releasing member strikes the extremity 5 of the swinging arm 30, pivotally mounted on the frame as shown, and is moved on the pins 20, 31 thereby and against the pressure of its spring 21, and into its initial position shown in Fig. 5, the spring 21 drawing 10 the releasable member sidewise sufficiently to cause the extension 24 of the slot 23 to holdingly engage the detent pin 20. When the rotatable member has completed its revolution, the pin 25 of the stop 26 falls 15 into the notch 27 and stops the clockwork. The stop 26 may be provided with an extending portion 32 adapted by the movement of the stop to engage the wind wheel 33 of the clockwork to stop the clockwork, and by 20 the movement of the stop to its releasing position to disengage the wind wheel.

It will be seen that by this invention, the clockwork is not suffered to run and the record strip is not paid out except when calls 30 are made.

The clockwork stopping action of the stop 26 may be exerted only to engage the wind wheel 33, it being a rotatable element of the clockwork. In such case the 35 notch 27 need not be stoppingly engaged by the pin 25 of the stop, and thus the stop may be more easily disengaged from its operative position owing to absence of friction between it and such notch.

40 The invention being intended to be defined solely by the claims, is not to be limited to or by details of construction shown or described.

I claim:

45 1. In combination with a telephone provided with calling apparatus, a movable member, means for operating the calling apparatus and for moving said member simultaneously, a marker with which said 50 movable member is operatively connected, a markable element movable relatively to the marker and adapted to be marked thereby, clockwork adapted to thus move the markable element, and means for stopping the 55 clockwork and releasable by the calling apparatus.

2. In combination with a telephone provided with calling apparatus, a movable member, means for operating the calling apparatus and for moving said member simultaneously, a marker with which said 60 movable member is operatively connected, a markable element movable relatively to the marker and adapted to be marked thereby, 65 clockwork adapted to thus move the mark-

able element, and means for stopping the clockwork and actuated automatically in a certain position of the clockwork and releasable by the clockwork.

3. In combination with a telephone provided with calling apparatus, an electromagnet, a member movable by said magnet, a marker with which said movable member is operatively connected, a markable element movable relatively to the marker and adapted to be marked thereby, clockwork adapted to thus move the markable element, and means for stopping the clockwork and carried thereby and releasable by the clockwork.

4. In combination with a telephone provided with calling apparatus, an electromagnet, a member movable by said magnet, a marker with which said movable member is operatively connected, a markable element movable relatively to the marker and adapted to be marked thereby, clockwork adapted to thus move the markable element, and means for stopping the clockwork and actuated automatically in a certain position of the clockwork and releasable by the clockwork.

5. In combination with a telephone provided with calling apparatus, a movable member, means for operating the calling apparatus and for moving said member simultaneously, a marker with which said movable member is operatively connected, a markable element movable relatively to the marker and adapted to be marked thereby, 100 clockwork adapted to thus move the markable element and comprising a rotatable element, a stop adapted to engage said element to stop the clockwork, and means for releasing the stop and operable by the means 105 for operating the calling apparatus.

6. In combination with a telephone provided with calling apparatus, a movable member, means for operating the calling apparatus and for moving said member simultaneously, a marker with which said movable member is operatively connected, a markable element movable relatively to the marker and adapted to be marked thereby, 110 clockwork adapted to thus move the markable element and comprising a rotatable element having a contact portion, a movable stop adapted to engage said contact portion 115 to stop the clockwork, and a movable releasing member adapted to be moved to release the stop from said contact portion by the means for operating the calling apparatus.

7. In combination with a telephone provided with calling apparatus, a movable member, means for operating the calling apparatus and for moving said member simultaneously, a marker with which said movable member is operatively connected, a markable element movable relatively to the 120

- marker and adapted to be marked thereby, clockwork adapted to thus move the markable element and comprising a rotatable element having a contact portion, a movable stop spring-pressed to engage said contact portion to stop the clockwork, and a releasing member slideable on the rotatable element and spring-pressed to release the stop from said contact portion and normally held against its spring by a detent, a swinging arm adapted to engage the releasing member and return it to the operative engagement of the detent, and means operable by the means for operating the calling apparatus for disengaging the releasing member from its detent. 8. In combination with a telephone provided with calling apparatus, a movable member, means for operating the calling apparatus and for moving said member simultaneously, a marker with which said movable member is operatively connected, a markable element movable relatively to the marker and adapted to be marked thereby, clockwork adapted to thus move the markable element and comprising a rotatable element, a movable stop adapted to engage said element to stop the clockwork and having a portion adapted to engage a wind wheel of the clockwork, and means for releasing the stop and operable by the means for operating the calling apparatus. 9. In combination with a telephone provided with calling apparatus, an electromagnet, a member movable by said magnet, a marker with which said movable member is operatively connected, a markable element movable relatively to the marker and adapted to be marked thereby, clockwork adapted to thus move the markable element and comprising a rotatable element, a stop adapted to engage said element to stop the clockwork and actuated automatically in a certain position of the clockwork and releasable by the clockwork. 10. In combination with a telephone provided with calling apparatus, a movable member, means for operating the calling apparatus and for moving said member simultaneously, a marker with which said movable member is operatively connected, a markable element movable relatively to the marker and adapted to be marked thereby, clockwork adapted to thus move the markable element and comprising a rotatable element, a movable stop adapted to engage said
- element to stop the clockwork, a second rotatable element having a peripheral notch adapted to receive a portion of the stop when the stop is in its operative position, and a movable releasing member adapted to be moved by the calling apparatus to move the stop's said portion out of the notch and thus release the stop's engagement with the first-mentioned rotatable member. 11. In combination with a telephone provided with calling apparatus, a movable member, means for operating the calling apparatus and for moving said member simultaneously, a marker with which said movable member is operatively connected, a markable element movable relatively to the marker and adapted to be marked thereby, clockwork adapted to thus move the markable element and comprising a movable element, a stop adapted to engage said element to stop the clockwork, and a releasing member to release the stop from its stopping engagement and operable by the means for operating the calling apparatus. 12. In combination with a telephone provided with calling apparatus, a movable member, means for operating the calling apparatus and for moving said member simultaneously, a marker with which said movable member is operatively connected, a markable element movable relatively to the marker and adapted to be marked thereby, clockwork adapted to thus move the markable element and comprising a rotatable element having a contact portion, a movable stop spring-pressed to engage said contact portion to stop the clockwork, and a releasing member slideable on the rotatable element and spring-pressed to release the stop from said contact portion and normally held against its spring by a detent, a swinging arm adapted to engage the releasing member and return it to the operative engagement of the detent, and means operable by the means for operating the calling apparatus for disengaging the releasing member from its detent. In testimony whereof I have hereunto set my hand in presence of two subscribing witnesses at Grand Rapids, Michigan, this 20th day of November A. D. 1916.

CHARLES E. BEDAUX.
